Specification for Design.

Patented Apr. 19, 1910.

Application filed February 5, 1910. Serial No. 542,328. Term of patent 3½ years.

To all whom it may concern:

Be it known that I, HENRY W. SCHWALB, a citizen of the United States, residing in the city of New York, borough of Manhattan, in the county and State of New York, have invented a new, original, and ornamental Design for a Hat-Pin, of which the following is a specification, reference being had to the accompanying drawing, forming part thereof.

The figure is a perspective view of a hat pin, showing my design in the form of an ornamental pendant hanging from the ornamental head of the pin.

I claim:

The ornamental design for a hat pin as shown and described,

HENRY W. SCHWALB.
